US0D1103616S

(12) **United States Design Patent** (10) Patent No.: **US D1,103,616 S**
(45) Date of Patent: ** Dec. 2, 2025

(54) **GUN HOLSTER**

(71) Applicant: **Cytac Technology Limited**, Shenzhen (CN)

(72) Inventor: **Yong Zhang**, Shenzhen (CN)

(73) Assignee: **Cytac Technology Limited**, Shenzhen (CN)

(**) Term: **15 Years**

(21) Appl. No.: **29/920,734**

(22) Filed: **Dec. 13, 2023**

(30) **Foreign Application Priority Data**

Oct. 26, 2023 (CN) 202330694687.3

(51) **LOC (15) Cl.** **03-01**

(52) **U.S. Cl.**

USPC **D3/222**; D22/108

(58) **Field of Classification Search**

USPC D3/222, 269, 328; D22/108, 199

CPC F41C 33/0209; F41C 33/02

See application file for complete search history.

(57) **CLAIM**

The ornamental design for a gun holster, as shown and described.

DESCRIPTION

FIG. 1 is a first perspective view of a gun holster showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the gun holster that form no part of the claimed design.

1 Claim, 8 Drawing Sheets
